Patented Mar. 2, 1920.

Inventor:
Charlie C. Colkitt
by John M. Potts
Atty.

UNITED STATES PATENT OFFICE.

CHARLIE C. COLKITT, OF PUNXSUTAWNEY, PENNSYLVANIA, ASSIGNOR TO COLKITT & BLEICH MANUFACTURING COMPANY REGISTERED, OF PUNXSUTAWNEY, PENNSYLVANIA, A LIMITED COPARTNERSHIP.

CLOTHESLINE-PROP.

1,332,323.

Specification of Letters Patent.

Patented Mar. 2, 1920.

Application filed February 1, 1919. Serial No. 274,441.

To all whom it may concern:

Be it known that I, CHARLIE C. COLKITT, a citizen of the United States, residing at Punxsutawney, county of Jefferson, and 5 State of Pennsylvania, have invented certain new and useful Improvements in Clothesline-Props, of which the following is a specification.

My invention relates to clothes props, that 10 is, to devices to be placed under a clothes line to support the same when in use.

The object of my invention is to provide a device of the character mentioned which will effectually prevent swaying of the line 15 in the wind which frequently results in breaking of the line. A further object of my invention is to provide a device of the character mentioned which, when not in use, may be folded into compact form to occupy 20 a minimum amount of space. A further object of my invention is to provide a device as mentioned equipped with improved means for holding the same in extended position. A further object of my invention is to provide 25 a device as mentioned which shall be of simple construction, easy to operate, and which shall not readily get out of order. Other objects will appear hereinafter.

With these objects in view, my invention 30 consists generally in a clothes prop comprising a pair of pivotally connected legs, a cross bar pivotally connected to one of said legs, a spring catch for securing the other end of the leg to the opposite leg when the latter 35 is in extended position, and a vertically adjustable arm provided with means for engaging the clothes line. My invention further consists in a device as set forth in which the legs are pivotally connected by 40 a pair of metal straps, one upon each side of the legs, and one of the straps shaped to form an eye through which the vertical arm is freely slideable, a similar eye on the cross bar to receive the lower end of the arm, and 45 means for adjustably securing the arm in position. My invention further consists in a device as mentioned of such construction that the legs will fold closely together, edge to edge, the extensible arm shall fold against 50 the sides of the legs, and the cross bar in the angular recess between one edge of the cross bar and the adjacent face of one of the legs. My invention further consists in various de-

tails of constructions and arrangements of parts all as will be fully described herein- 55 after and particularly pointed out in the claims.

My invention will be readily understood by reference to the accompanying drawings forming a part of this specification and in 60 which—

Figure 1 is a side elevation of a clothes prop embodying my invention, illustrating the same in extended position.

Fig. 2 is a detail elevation illustrating the 65 opposite side of the device, the upper portions of the arm and the lower portions of the legs being broken away.

Fig. 3 is a side elevation of the device.

Fig. 4 is an elevation of the device in 70 folded position.

Fig. 5 is a similar view illustrating the opposite side from that shown in Fig. 4.

Fig. 6 is a transverse section on the line 6—6 of Fig. 5, upon an enlarged scale, and 75

Figs. 7 and 8 are details of the latch for securing the cross bar to one of the legs.

Referring now to the drawings, 1 and 2 indicate the legs of the device which are pivotally connected at their upper ends by 80 metal straps 3 and 4 arranged upon opposite sides thereof. The strap 3 is preferably a straight piece of metal, whereas the strap 4 is bent to form a rectangular eye 5 for a purpose hereinafter described. These straps 85 are secured to the legs a short distance from the upper ends thereof and the portions of the legs above said straps are beveled, as indicated at 6, to form shoulders which abut when the device is in extended position, as 90 shown clearly in Fig. 2. The lower ends of the legs are pointed, as at 7, to firmly engage the ground. Pivotally connected, at 8, to the leg 2 is a cross bar or brace 9, the free end of which is adapted to engage a 95 spring latch 10 on the leg 1 when the device is in extended position. It should be noted that the pivot 8 is arranged adjacent the upper edge of the bar 9 and adjacent the outer edge of the leg 2 for a purpose hereinafter explained. The latch 10 is formed of a strip of spring metal bent to form an attaching base 11 bent outwardly and upwardly forming a socket 12 to receive the brace bar, then slightly inward, as at 13, to 105 engage the upper edge of the same to hold it

in position, and then curved outwardly, as at 14, to facilitate the passage of the end of the bar between the same and the leg 1 into the socket 12. The bar 9 is preferably 5 provided with a notch 15 in its lower edge to engage the outwardly extending portion of the socket 12. It is evident that by this construction the brace bar may be readily slipped in position and automatically 10 locked. The outer face of the brace bar 9, adjacent its upper edge, is provided with an eye 16 formed of a metal strap, similar to the eye 5.

Slidably mounted through the eye 5 is 15 an upwardly extending arm 17 which is provided at its upper end with line-engaging means 18, which is preferably in the form of a coiled spring wire, as illustrated in the several figures of the drawings. When the 20 device is in extended position, the lower end of the arm 17 is positioned in the eye 16 on the brace bar 9, the two spaced eyes 5 and 16 thereby firmly holding the same in position. The arm is provided with a plurality of 25 apertures 19 adapted to receive a pin 20 which rests upon the upper edge of the bar 9 and eye 16 and by means of which the arm may be adjusted to the desired height.

To fold the device, the arm is raised out 30 of the eye 16, the brace 9 disengaged from the spring 10 and swung downwardly, the legs folded together and the arm slid downwardly into the position shown in Figs. 4 and 5. By positioning the pivot 8 of the 35 arm 9 as above described said arm will fit snugly in the angular recess formed between one edge of the arm 17 and the adjacent face of the leg 2, as shown clearly in Fig. 5. It

will be noted that with the construction above mentioned the device will fold into 40 compact form to occupy a minimum amount of space.

I claim:

1. A clothes prop comprising a pair of legs pivotally connected at their upper ends, 45 a brace bar pivotally connected to one of said legs, means for detachably connecting the free end of the brace to the opposite leg, an eye at the upper end of said legs, a similar eye on said brace, an arm slidably mounted in said eyes and provided at its upper end with line-engaging means, and means for supporting said arm in adjusted position, substantially as described.

2. A device as set forth in claim 1 in 55 which the pivotal connection between the brace and the leg is arranged adjacent the upper edge of the brace and the outer edge of the leg to facilitate compact folding of the device, substantially as described.

3. A device as set forth in claim 1 further characterized by a spring catch on one of the legs adapted to receive the free end of the brace, there being a notch in the brace to receive a portion of said spring catch and 60 means on said catch to hold the notched portion of the brace in engagement with the catch, substantially as described.

In testimony whereof I have signed my name to this specification in the presence of 70 two subscribing witnesses.

CHARLIE C. COLKITT.

Witnesses:
